UNITED STATES PATENT OFFICE.

FRANK M. THOMPSON, OF EAST LIVERPOOL, OHIO, ASSIGNOR OF ONE-HALF TO SILAS MENOUGH, OF COLUMBIANA COUNTY, OHIO.

VELOCIPEDÉ.

No. 808,616.

Specification of Letters Patent.

Patented Dec. 26, 1905.

Application filed February 18, 1905. Serial No. 246,237.

To all whom it may concern:

Be it known that I, FRANK M. THOMPSON, a citizen of the United States, and a resident of East Liverpool, in the county of Columbiana and State of Ohio, have invented certain new and useful Improvements in Velocipedes, of which the following is a specification.

My invention is an improvement in velocipedes, and relates especially to that class of such devices which is represented in my former patent, No. 783,912, dated February 28, 1905.

The present invention has for an object, among others, to provide for excluding the connections between the front and rear legs from view and for supporting the front of the sulky in such manner as to relieve the strain of such support from the imitation figure of a horse and to provide for a spring connection between the upper and lower leg-sections and for an adjustable seat for the sulky; and the present invention consists in certain novel constructions and combinations of parts, as will be hereinafter described and claimed.

In the drawings, Figure 1 is a side view of a velocipede embodying my invention. Fig. 2 is a vertical longitudinal section of an imitation horse. Fig. 3 is a detail vertical section drawn through the seat of the sulky, and Fig. 4 is a cross-section on about line 4-4 of Fig. 1, on a somewhat reduced scale.

The sulky has its axle A provided with cranks B, which are connected by pitmen C in connection with the sulky in advance of the seat E, the latter being slotted at E' in direction of length of the sulky, and the seat-fastening bolts E² being passed through the slot E', so the seat can be adjusted back and forth to suit the size of the rider. It will be understood that as the treadles are operated the sulky will be propelled.

The imitation figure of a horse F is supported between the shafts G of the sulky and is made hollow to receive certain parts presently described, and the steering-wheel H has its shaft H' journaled vertically in the figure of the horse and preferably within a sleeve I, arranged within the horse, and having flanges I' at its opposite ends to form a broad bearing against the upper and lower portions of the hollow shell, such flanges I' being preferably formed on collars I², secured upon the sleeve I, as will be understood from Fig. 2 of the drawings. To brace the figure

of the horse and to relieve the latter as far as possible from the strain of the steering-shaft, I provide a brace-frame connecting the shaft of the steering-wheel above and below the figure of the horse with the shafts G of the sulky. This frame extends around the outer side of the figure F and preferably comprises upper and lower bars J j J' j'. The bars J j extend forwardly at an incline to their juncture at J² with the shafts G, and the bars J' j' extend rearwardly at an incline to their juncture J² with the shafts, the frame being thus connected in front and rear of a cross-sectional line drawn through the horse and which would intersect the shaft H'. I thus provide a strong frame for supporting the steering-shaft directly from the shafts of the sulky. Driving-lines may be connected with a cross-bar I³ at the upper end of the shafts, (see Fig. 4,) and the lines may extend thence to the head of the horse, as shown in Fig. 1. The legs of the horse are composed of upper and lower sections K, K', L, and L', the upper sections being pivoted at K² and L² to the body of the figure, and the lower sections being pivoted at their upper ends at K³ and L³ to the lower ends of the upper sections. Spring-bars K⁴ and L⁴ are secured at K⁵ and L⁵ to one of the leg-sections and slide at K⁶ and L⁶ in connection with the other leg-section, as best shown in Fig. 2, and in such manner that the leg-sections will be held normally straight, will be returned when free to the straight position, and yet may be moved to give the desired action to the horse by the means presently described. The upper leg-sections have a limited movement on their pivots K² and L², stop devices being provided at k and l to limit the movement of the said sections, so that when they have been moved by the operating devices to their full extent the lower leg-sections will be given a further movement to secure the desired action.

In constructing the imitation of a horse it is important to hide as far as possible all the operating devices for producing the simulated action of the horse, whether it be pacing or trotting, and to this end I make the figure of the horse hollow and provide the front and rear levers M and N, which are pivoted at M' and N' within the body of the horse concentric with the pivots K² and L² and have their upper ends or arms connected by the bars O and their lower ends slidably connected at M² and N² with the lower front and rear leg-sections.

The bars O may connect the front and rear levers on the same side of the horse to give a pacing action, or may be crossed in securing a trotting action as desired. The rear levers 5 M have their lower arms connected by pitmen P with the treadles D, so that the levers M and N will be operated in working the velocipede.

As shown in Fig. 1, I am able to dispense 10 with all exterior or exposed connections between the front and rear legs of the figure of the horse and to secure the action of the front and rear legs in a manner closely simulating nature.

15 Having thus described my invention, what I claim as new, and desire to secure by Letters Patent, is—

1. The combination in an apparatus substantially as described of the sulky having a crank-

20 axle and the shafts, the imitation horse secured between the shafts and having a hollow body and front and rear legs composed each of upper sections pivoted at their upper ends to the body and lower sections pivoted at their

25 upper ends to the lower ends of the upper sections, springs extending across the joint between the upper and lower leg-sections and connected with said leg-sections, levers pivoted between their ends concentric with the

30 pivotal connections of the upper leg-sections with the body and having their upper arms extended into the body of the horse, rods connecting the upper ends of the front and rear levers and extending within the body of the

35 horse, the steering-wheel, and the bracing-frame connected with the shaft of the steering-wheel and extending around the body of the horse and secured between its ends to the shafts of the sulky, substantially as set forth.

40 2. The combination with the sulky-shafts and the steering-wheel, of the imitation figure secured between the shafts and the bracing-frame connected between its ends with the shafts and extending around the body of the

figure and connected with the steering-wheel, 45 substantially as set forth.

3. The combination with the imitation figure and the sulky-shafts of the steering-wheel having its shaft journaled vertically in the figure, and the bracing-frame connected with said 50 steering-shaft above and below the figure and secured between its ends to the sulky-shafts, substantially as set forth.

4. The combination of the sulky-shafts and the figure secured between said shafts, the 55 steering-wheel shaft journaled in the figure, the bracing-frame secured to said steering-shaft above and below the figure and extending around said figure and having front and rear bars inclined, respectively, forwardly and 60 rearwardly to their juncture with the sulky-shafts and secured to the shafts, substantially as set forth.

5. The combination of the sulky-shafts, the hollow imitation figure, the steering-wheel 65 shaft extending through the said figure, the sleeve on said shaft within the figure and bearing at its ends against the upper and lower walls thereof, and the bracing-frame connected with the steering-shaft above and below the 70 figure and extending around the latter and secured to the sulky-shafts, substantially as set forth.

6. The combination with the imitation figure having a body and legs composed of upper sections pivoted to the body and lower sections pivoted to the upper sections, levers pivoted between their ends and extending downwardly past the joint between the leg-sections and having their lower ends connected with the 75 lower leg-sections, connections between the upper ends of said levers, and means for operating the levers, substantially as set forth.

FRANK M. THOMPSON.
